DESIGN FOR A FAN CASING

William J. Campbell, Indianapolis, Ind., assignor
to Climax Machinery Company, Indianapolis,
Ind., a corporation of Indiana

Application January 18, 1945, Serial No. 117,495

Term of patent 14 years

(Cl. D26—7)

To all whom it may concern:

Be it known that I, William J. Campbell, a citizen of the United States, residing at Indianapolis, in the county of Marion and State of Indiana, have invented a new, original, and ornamental Design for a Fan Casing, of which the following is a specification, reference being had to the accompanying drawing forming a part thereof.

In the drawing

Fig. 1 is a front perspective view of a fan casing, showing my new design; and

Fig. 2 is a rear elevational view thereof, drawn to a slightly smaller scale.

The two ends of my fan casing are substantially identical.

I claim:

The ornamental design for a fan casing, as shown and described.

WILLIAM J. CAMPBELL.
